UNITED STATES PATENT OFFICE.

JOHN F. PRICE, OF NASHVILLE, ARKANSAS.

VOTING-MACHINE.

1,180,184.

Specification of Letters Patent. Patented Apr. 18, 1916.

Application filed September 21, 1914. Serial No. 862,795.

To all whom it may concern:

Be it known that I, JOHN F. PRICE, a citizen of the United States, residing at Nashville, in the county of Howard and

5 State of Arkansas, have invented certain new and useful Improvements in Voting-Machines; and I do hereby declare the following to be a full, clear, and exact description of the invention, such as will enable 10 others skilled in the art to which it appertains to make and use the same.

This invention relates to improvements in voting machines and the primary object of the invention is the provision of a voting 15 machine which will imprint a permanent record synchronously with the punching of the keys, whereby all controversy relative to the improper counting of votes may be eliminated.

20 Another object of this invention is the provision of a voting machine which embodies a plurality of type bars which are controlled by the energizing of electrical magnets for imprinting characters upon 25 suitable paper.

A further object of this invention is the provision of a mechanism whereby said electrical magnet will be energized upon the punching of any key for registering a vote.

30 A still further object of the invention is the provision of a novel and simple form of mechanism for locking the key in an operated position.

With the foregoing and other objects in view this invention consists in such novel features of construction, combination and arrangement of parts as will be hereinafter more fully described, illustrated in the accompanying drawings and claimed.

40 In describing the invention in detail reference will be had to the accompanying drawings wherein like characters designate like or corresponding parts throughout the several views, and in which:—

45 Figure 1 is a diagrammatic plan view of the improved voting machine showing the electrical connections between the various keys and the electrical magnets operated synchronously therewith. Fig. 2 is a central sectional view through the improved voting machine. Fig. 3 is a plan view of the 50 electrical magnets and the type bar actuating levers. Fig. 4 is a fragmentary plan view of one of the recording rolls and of the contact for closing a circuit for energizing an electrical magnet. Fig. 5 is a side ele-

vational view of Fig. 4 showing a fragment of one of the voting keys. Fig. 6 is a fragmentary plan view of a part of the key locking mechanism. Fig. 7 is a cross sectional view through a part of the key locking mechanism. Fig. 8 is a fragmentary view in elevation of one electrical magnet showing the type bar and the lever for actuating the same, and Fig. 9 is a detail view of the 65 voting keys.

Referring more particularly to the drawings, 1 designates the outer casing of the voting machine, which has an inclined base partition 2 secured therein and a vertical partition 3, which vertical partition extends transversely across the casing adjacent the larger end thereof, for forming a compartment for retaining the electrical magnets. The compartment 4 which is formed by the 70 partition 3 has a transversely extending base 5 extending thereacross, the purpose of which will be hereinafter more fully described. The casing 1 has a door 6 hingedly connected thereto as is shown at 7, to permit 75 of access to the interior of the casing for the repairing of the various mechanisms mounted therein when necessary.

The top 9 of the casing 1 is provided with a plurality of openings 10 spaced in rows 80 longitudinally and laterally thereof, in which openings are slidably seated voting keys 11. The voting keys 11 have heads 12. The heads 12 have plates 13 mounted thereupon which have their marginal edges bent 85 inwardly as is clearly shown in Fig. 9 of the drawings, for receiving a ticket or printed slip which bears the name of the candidate. The shanks 14 of the voting keys extend 90 downwardly through the openings 10, and have notches 15 formed in their edges, which notches are provided for receiving the free ends of pivoted locking pawls 16. The pivoted locking pawls 16 are pivoted upon pins 17, which are carried by the top 9 of the 95 casing 1 and extend downwardly therein, and they have spiral springs 18 connected thereto forwardly of their pivotal point as is clearly shown in Fig. 6 of the drawings. The spiral springs 18 are secured to the 100 under surface of the top 9 of the casing 1, and they tend to draw the free end of the locking pawl 16 toward the shank at all times. When the keys 11 are forced downwardly or punched for registering a vote 105 for various candidates, the free ends of the locking pawls 16 will, by the contracting 110

action of the spiral springs 18 spring into the notches 15 and hold the keys in an inward position until the key releasing rod 19 is actuated. The key releasing rod 19 is 5 journaled in suitable bearings at one end of the compartment in which the keys are mounted, and it has a handle 20 secured thereto for rocking the shaft or rod. Bars 21 extend longitudinally within the casing 1 and are slidably carried by brackets 22, which are secured to the under surface of the top end 9. The bars 21 are provided with notches 23 formed therein and having square shoulders 24, which square shoulders are 10 provided for engagement with the free ends of the locking pawls 16 for moving these pawls upon the pivotal pins 17 for moving them out of the notches 15 when the releasing rod 19 is rocked. The bars 21 have 15 slots 25 formed therein adjacent their rear ends which are positioned above the lock releasing rod 19. The lock releasing rod 19 has collars 26 mounted thereupon, which have spindles 27 and 28 projecting therefrom diametrically opposite to each other. The spindles 27 extend upwardly and are seated in the slots 25 formed in the bars 21 so that when the rod 19 is rocked by the actuation of the handle 20, the bars 21 will be 20 moved longitudinally, for moving the locking pawls 16 upon their pivotal points 17 and out of the notches 15 which are formed in the voting key shanks 14. The arms 28 extend downwardly from the collar 26 and 25 they have spiral springs 29 secured thereto. The spiral springs 29 are also connected to lugs which are carried by the casing 1 so that immediately after pressure is released from the handle 20 the spring will contract, rocking 30 the rod 19 and causing it to assume its normal position preparatory to the sliding of the released bars 21.

Each of the keys 11 has a counter 31 positioned therebeneath, which counters are of 40 the ordinary rotary type having a plurality of wheels for counting or registering each depression or punching of the respective key with which it coacts. The counters or registers 31 have ratchet wheels 32 secured thereto for rotating the respective counting wheels. Arms 33, which are pivotally mounted on rods 34, are provided for engaging the teeth of the ratchet wheel 32 for rotating the registering wheels of the counters 50 upon each depression or punching of the voting keys. The arms 33 have arcuate sections 35, and the flat sections 36, which latter sections engage the ratchet wheel 32.

The arcuate sections 35 of the arms 33 have enlarged heads 37 formed thereupon. The enlarged heads 37 of the arms 33 have insulating plates 38 secured to their under surface, and conductive contact plates 39 secured to the under surface of the insulating plates 38. The conductive contact

plates 39 are provided for engagement with upstanding contacts 40 and 41 when the voting key is depressed for actuating or registering a vote for a candidate. The depression of the voting key will force the 70 head 37 downwardly and cause the same to engage the upper ends of the upstanding contacts 40 and 41 which will close an electrical circuit through these contacts, and through the electrical magnet indicated by 75 the numeral 42 which corresponds with the voting key punched.

In Fig. 1 of the drawings a diagrammatic view of the arrangement of the voting keys and the electrical magnet 42 is 80 shown. The upstanding contacts 40 are each and every one connected to a battery 50 or other suitable electrical supply source, while the contacts 41 are connected through the medium of electrical conductors 43 with 85 one pole of electrical magnet 42, which corresponds with the voting key beneath which the upstanding contacts are mounted. For instance in Fig. 1 of the drawings, the contact 40 which is positioned beneath the key 90 A has communication with the battery, and the contact 41 which is positioned beneath the key A has communication with one pole of electrical magnet B which corresponds with the key A. The other pole of electrical magnet has direct communication with the opposite pole of the battery 50 through an electrical conductor 44. Each and every one of the keys is connected in the manner heretofore described with the electrical magnet which corresponds therewith, as is clearly shown in the diagrammatic view of the voting machine, so that when the key is depressed for recording a vote for the candidate which it represents, an electrical magnet corresponding with the key will be energized for imprinting a permanent record of the vote in the manner hereinafter more fully described.

The electrical magnets have contact levers or armatures 45 positioned above their uppermost end. The contact levers 45 are pivotally mounted on rods 46, which extend transversely through the compartment 4. The rods 46 are supported by suitable supporting arms 47, which depend from the top 48 of the compartment 4. The contact levers 45 have type bar carrying rods 48 connected to their outer free ends, which bars extend downwardly through the supporting plate 49. The supporting plate 49 supports the electrical magnets 42 and it has positioned therebeneath a piece or strip of paper 51, above which is mounted an inking ribbon 52. Each of the keys 11 is 110 numbered, as is shown at 53 in Fig. 1 of the drawings, and the bars 48 have types 54 carried by their lower ends which bear the indicating character or number corresponding with the indicating character or 115 120 125 130

number of the key which is operatively connected to the electrical magnet 42 adjacent which the bar 48 is mounted.

When one of the keys 11 is pressed downwardly, for instance when the key A is pushed downwardly for voting for the candidate which the key indicates, the circuit will be closed between the upstanding contacts 40 and 41 which are positioned therebeneath, which will energize the magnet 42 corresponding thereto and cause the armature lever 45 to move downwardly and engage the upper magnet 55 of the electrical magnet 42, which will force or jam the rod 48 downwardly causing the same to imprint through the inking ribbon 52, its indicating character 54 upon the paper ribbon 51 which is positioned therebeneath for permanently recording the vote for said candidate. The levers 45 have spiral springs 56 secured thereto, which springs return the levers to a horizontal position, and move the characters 54 out of engagement with the ribbon 52, immediately upon the releasing of the various keys 11 by the pawls 16, after the entire vote has been cast and thus providing a permanent record of the casting of the vote.

The arms 33 have spiral springs 56 secured thereto, for returning them to their normal position after having been operated by the depression of the keys 11. The shanks 14 of the keys 11 have contracting spiral springs 57 secured thereto, which springs are also secured to the under surface of the top 9 of the casing. The springs 57 are provided for automatically forcing the keys 11 upwardly after they have been released by the actuation of the releasing bars 21 and the releasing rod 19.

The casing 1 has the upper section thereof hingedly connected to the upper edge of the magnet supporting casing as is shown at 60. The upper section of the casing 45 which is hingedly connected to the main body portion thereof carries the keys 11, and it is hingedly connected so that after the complete vote has been cast the upper section may be removed for permitting views 50 of the various counters 31 which are positioned therebeneath. A latch or catch 61 is secured to the forward end of the hinged section of the casing 1 and it is provided for attachment with the forward edge of the casing 1 for holding the hinged section downwardly or in a locked position upon the casing 1 during the voting.

In the operation of the improved voting machine heretofore described, when an election is to be held, cards designating the various candidates are inserted in the plates 13 which are carried by the heads 12 and the keys 11 and a person voting pushes or depresses keys which carry the names of the candidates for which he wishes to vote. The

depression of the keys actuate the counters 31 as has been heretofore described and also close the electrical circuit through the respective electrical magnet 42 for printing a permanent record of the vote cast. After 70 the voter has depressed keys corresponding with each and every candidate for which he is entitled to vote and desires to vote, the handle 20 is actuated which rocks the releasing rod 19 and moves the releasing bars 21 75 longitudinally in the manner heretofore described. The longitudinal movement of the releasing bars 21 will engage the pawls 16 and move them out of the notches 15 which are formed in the shanks 14 of the keys 11. 80 The springs 57 will then return the keys 11 to their normal position. The springs 56 will return the arms to their normal position. Upon the returning of the levers 33 to their normal position the contact 39 will 85 be moved from engagement with the upper ends of the contacts 40 and 41 and the circuit will be broken between these contacts and the electrical magnet 42 corresponding therewith.

From the foregoing description taken in connection with the accompanying drawings the advantages of the construction and of the method of operation of the improved voting machine will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of 105 what is claimed.

What is claimed is:

1. In a voting machine, the combination of a plurality of depressible keys, a plurality of electrical magnets connected correspondingly to said depressible keys, armature contact levers pivoted above said electrical magnets, type carrying bars carried by said pivoted armature levers, an ink ribbon positioned beneath the ends of said type carrying bars, a strip of paper mounted beneath said ink ribbon, and means whereby when one of said keys is depressed, the electrical magnet corresponding thereto will be energized for operating said pivoted lever and said type carrying bars.

2. In a voting machine, the combination, of a plurality of depressible keys, a plurality of electrical magnets connected correspondingly to said depressible keys, armature contact levers pivoted above said electrical magnets, type carrying bars carried by said pivoted armature levers, an ink ribbon positioned beneath the ends of said type carrying bars, a strip of paper mounted

beneath said ink ribbon, means whereby when one of said keys is depressed the electrical magnet corresponding therewith will be energized for operating said pivoted lever and said type carrying bars, and means for holding each of said keys in a depressed position after having been depressed for a predetermined length of time.

3. In a voting machine, the combination, 10 of a plurality of depressible keys, a plurality of electrical magnets connected correspondingly to said depressible keys, armature contact levers pivoted above said electrical magnets, type carrying bars connected 15 to and carried by said pivoted armature levers, an ink ribbon positioned beneath the ends of said type carrying bars, a strip of paper mounted beneath said ink ribbon,

means whereby when one of said keys is depressed the electrical magnet corresponding therewith will be energized for operating said lever and said type carrying bars, means for holding each of said keys in a depressed position after having been depressed for a predetermined length of time, means 20 for releasing all of said keys depressed synchronously, and means for returning said pivoted contact levers to their normal position upon the deenergizing of said electrical magnets. 25

In testimony whereof I affix my signature in presence of two witnesses.

JOHN F. PRICE.
